UNITED STATES PATENT OFFICE.

DAN L. COBB AND WILLIAM W. MOORE, OF ORANGE, TEXAS.

DUBBING-MACHINE.

1,306,249.

Specification of Letters Patent. Patented June 10, 1919.

Application filed March 1, 1918. Serial No. 219,933.

To all whom it may concern:

Be it known that we, DAN L. COBB and WILLIAM W. MOORE, citizens of the United States, residing at Orange, in the county of Orange and State of Texas, have invented certain new and useful Improvements in Dubbing-Machines, and we do hereby declare the following to be a full, clear, and exact description of the invention, such as will enable others skilled in the art to which it appertains to make and use the same.

This invention relates to dubbing machines, and the primary object of the invention is the provision of an improved machine for dressing ship timber, so that the same can be quickly and readily prepared.

Another object of the invention is the provision of a portable machine carrying a motor and a rotatable cutter head for dressing any type of ship timber after the same has been placed in position to build the framework of a ship.

A further object of the invention is the provision of a portable dressing machine having a rotatable cutter head and supporting wheels for engaging a track secured to the sides of the timber to be dressed, the wheels and cutter head being adjustable, so that the machine can be used for any size and type of timber.

A still further object of the invention is to provide an improved machine of the above character, which is durable and efficient in use, one that is simple and easy to manufacture, and one that can be placed upon the market at a reasonable cost.

With these and other objects in view, the invention consists in the novel construction, arrangement and formation of parts, as will be hereinafter more specifically described, claimed, and illustrated in the accompanying drawings, forming a part thereof, in which:

Figure 1 is a plan view of the improved dubbing machine,

Fig. 2 is a side elevation of the improved machine, showing the same in operative position on a timber to be dressed,

Fig. 3 is a front elevation, partly in section, of the improved machine, showing the same in position on a timber to be dressed,

Fig. 4 is a side elevation of one of the adjustable wheels mounted on the driving

spindle for engaging the rails nailed to the timber to be dressed,

Fig. 5 is a detail section, taken on the line 5—5 of Fig. 4,

Fig. 6 is a transverse section taken through the improved cutter head on the line 6—6.

Referring to the drawings in detail, wherein similar reference numerals designate corresponding parts throughout the several views, the numeral 1 generally indicates the improved machine, and 2 the timber which is to be dressed. The improved machine 1 comprises a frame 3 formed of a pair of spaced longitudinally extending bars 4 held together against relative movement by brace irons 5, which extend laterally of the side bars 4. Suitable cross beams may be positioned between the brace rods 5 and secured to the side bars 4 for holding the frame against all strains. The forward ends of the side bars 4 are provided with enlarged bearings 6 for rotatably receiving the shaft or spindle 7. One end of the shaft protrudes outwardly through one of the side bars 4, and is provided with a drive pulley 8. The rear end of the frame 2 is provided with a hanger 9 for receiving a motor 10 for driving the shaft 7. The cradle 9 consists of a supporting bar 11 extending parallel with the side bars and running from the rear brace rods 5 to the adjacent brace rods 5, and this bar 11 is connected with one of the side bars 4 by supporting bars 12, which receive the base 13 of the motor. Any suitable type of motor may be employed for driving the shaft 7, and, as illustrated in the drawings, an electric motor is provided, and the armature shaft 14 thereof is extended outwardly from the motor toward one of the side bars 4, while the same is journaled in a bearing 15 secured to a supporting block 16 bolted, as at 17, to the rear portion of the side bar 4. The outer end of the armature shaft 14 is provided with a drive pulley 16, and the pulley 16 is connected with the pulley 8 of the shaft 7 by means of a belt 17.

The power for running the motor may be obtained from any suitable source, and a switch 18 is provided for controlling the operation of the same.

The shaft 7 is provided with a pair of dia-

metrically opposed ribs 19, which extend longitudinally of the shaft, and mounted for movement with the shaft and movement longitudinally of the shaft is a cutter head 20. Set screws 21 are carried by the cutter head for engaging the shaft, so as to lock the head in any desired position. The cutter head may be of any preferred form, and as shown the same is substantially rectangular in cross section, and receives a pair of cutting or dubbing knives 22. Set screws 26 extend through slots 24 formed in the blades and into the head 20, and provide means for adjustably holding the blades in position. Thus the blades can be adjusted inwardly or outwardly of the head, as desired. Slidably mounted on the shaft on each side of the cutter head 20 is a block 25, each of which carries a depending bracket 26, carrying a stub shaft 27, which rotatably supports a wheel 28. The block is preferably formed of solid brass, and is provided with an aperture for rotatably receiving the bushing 29, which is provided with slots 30 for receiving the keys or ribs 19, and the bushing 29 revolves with the shaft. Suitable locking rings 31 are mounted on each side of the block 25 on the bushing 29, and carry a locking set screw 32, whereby the rings 31 can be held in position for rotation with the bushing. These rings prevent independent movement of the block 25 with relation to the bushing 29. A U-shaped yoke 33 has the terminals of its downwardly extending legs bolted, as at 34, to the upper surface of the block 25, and secured to the upper surface of the U-shaped members at the central portion thereof is a cross rod 35, which has its ends bent downwardly, as at 36, to receive the fastening element 37, which holds the same in position. By removing the brace rod 34 the blocks can be readily slid on the shaft 7 to bring the wheels 28 toward or away from each other, and different size brace rods 35 are provided so that the wheels can be held in any desired position with relation to each other. Suitable rearwardly extending braces 38 are formed on the lower ends of the depending brackets 26. These brace rods extend upwardly and rearwardly from the brackets to a transversely extending rod 39, which slidably supports the same. The rod 39 has its ends secured to the side bars 4. The ends of the wheel brace rods 38 are enlarged, as at 40, and are apertured, so that the same may be slidably mounted on the rods. Bearings 41 are secured to the surface of the side bars 4 adjacent the rear ends thereof, and these bearings support a shaft 42, which extends transversely of the frame. This shaft receives a relatively long roller 43, and the same is positioned in a plane above the wheels 28.

In operation of the improved machine the rails 44 are temporarily secured by any suit-

able fastening elements to the sides of the timber 2, which is to be addressed, and the wheels 28 are adjusted in the manner described above, so as to engage the sides of the timber and the rails 44. The wheels 28 engaging the sides of the timber prevent relative or lateral movement of the machine on the timber and hold the same in its course. The relatively long roller 43 engages the top surface of the timber being dressed and forms a support for the rear end of the frame. The cutter head 20 is adjusted on the shaft 7 in the above described manner, and the switch is then operated, so that the motor 10 is started. The machine is then drawn over the timber to be dressed. It can be seen that the motor 10 can either be of the reversing type, or the belt 17 can be twisted so as to reverse the direction of the shaft 7 when so desired. After a certain width of the timber has been dressed the cutter head is slid along the shaft and locked and another portion of the timber dressed, until the whole surface of the same is smooth.

Suitable handles, not shown, can be secured to either the front or rear end of the machine, and these handles form means whereby the machine can be guided and drawn over the work.

While the machine has been shown on rectangular timber, it is to be understood that the same can be used for dressing round, octagon, square or other shaped timber, and can be used for inside and outside work on frames of a ship, or for both vertical and horizontal timbers.

From the foregoing description, taken in connection with the drawings, it can be seen that an improved machine is provided, which is especially adapted for dubbing or dressing the vertical and horizontal inside and outside frames of wooden ships, beveling planks, working around timbers, octagon or square, and one which will quickly and efficiently do the work which is to be done.

In practice, we have found that the form of our invention illustrated in the accompanying drawings and referred to in the above description, as the preferred embodiment, is the most efficient and practical; yet realizing the conditions concurrent with the adoption of our device will necessarily vary, we desire to emphasize that various minor changes in details of construction, proportion and arrangement of parts may be resorted to, when required without sacrificing any of the advantages of our invention as set forth.

Having thus described our invention what we claim as new, is:

A portable dubbing machine comprising a frame, a rotatable shaft carried by the forward portion of the frame and positioned below the same, a cutter head keyed to the

shaft, a motor for operating the shaft, blocks mounted on each side of the cutter head and slidably mounted on the shaft, a bushing rotatably carried by the blocks and keyed to the shaft, a depending bracket formed on the blocks, rollers rotatably carried by the bracket, and means for holding the blocks in spaced relation to each other.

In testimony whereof we affix our signatures in presence of two witnesses.

DAN L. COBB.
WILLIAM W. MOORE.
